UNITED STATES PATENT OFFICE.

ERWIN R. JONES, OF COLUMBUS, OHIO.

TWINE CUTTER.

Application filed May 2, 1923. Serial No. 636,099.

To all whom it may concern:

Be it known that I, ERWIN R. JONES, a citizen of the United States, residing at Columbus, in the county of Franklin and State 5 of Ohio, have invented certain new and useful Improvements in Twine Cutters, of which the following is a specification.

The present invention is directed to improvements in twine cutters.

10 The primary object of the invention is to provide a device of this character so constructed that twine can be conveniently severed when the device is resting upon the counter or the like or it can be easily manipulated for severing twine upon packages of such weight as to not be conveniently lifted.

15 A further object of the invention is to provide a device of this character constructed in such manner that the cutting blade can be conveniently manipulated to cut pasteboard containers or the like, thereby providing a combination twine cutter and container opener.

20 With these and other objects in view, as will appear as the description proceeds, the invention consists in the novel features of construction, combinations of elements and arrangements of parts, and hereinafter to be 25 fully described and pointed out in the appended claims.

In the accompanying drawing:

Figure 1 is a side elevation of the device,

25 Figure 2 is a longitudinal sectional view therethrough,

Figure 3 is a sectional view on line 3—3 of Figure 1,

Figure 4 is a sectional view on line 4—4 of Figure 2,

30 Figure 5 is a fragmentary longitudinal sectional view showing the cutting blade in its extended position,

Figure 6 is a detail perspective view of the cutting blade and its associated block.

35 Referring to the drawing 1 designates a base having a vertical post 2 rising therefrom, said base being capable of being fixed to a counter or the like if desired. A hollow metallic handle 3 is employed and

40 has its lower end formed with a socket 4 for detachable engagement with the post 2, whereby the handle can be quickly removed or replaced. The handle 3 has cast therewith a sleeve 5 and transversely spaced vertical fingers 6 and 7, there being a longitudinal groove 8 formed in the inner face

of the finger 6 and which terminates in a groove 9 in the collar 5, said collar being further provided with an annular shoulder 10, the purpose of which will appear later. 60 Also cast with the collar 5 are spaced webs 11 which terminate in vertical spaced guide plates 12, the upper ends of which are curved as at 13.

65 The cutting blade 14 includes a base 15 which normally rests on the shoulder 10 and is formed with a recess 16 for slidably receiving the clamping block 17, said block having spaced end wings 18 which embrace the adjacent parts of the base 15. This 70 block has a threaded bore 19 in which is engaged a thumb screw 20. Thus it will be seen that when the blade is in its assembled position that the back of the block and wings will engage the inner wall of the collar 5 and when the thumb screw is turned inwardly the end thereof will be impinged against the base of the recess 16 thereby forcing the block outwardly into the frictional engagement with the collar and the 80 back of the plate in tight engagement with the bases of the grooves 8 and 9, thereby holding the blade against accidental movement. To accommodate the screw 20 a slot 21 is formed in the collar 5 and extends into 85 the adjacent finger 7.

85 The cutting edge 22 of the blade for a major distance of its length is received in the space between the plates 12 so that when the twine to be severed is forced between the 90 plates and blade it will be guided directly to the cutting edge of the blade and severed.

95 The outer edge of the blade 14 and base 15 are capable of sliding in the grooves 8 and 9 and are consequently held against lateral movement, but can slide freely.

100 When it is desired to slide the blade 14 outwardly so that the end thereof will extend beyond the ends of the fingers 6 and 7 it is only necessary to manipulate the thumb screw 20 to release the block 17, whereupon forcing the screw outwardly the blade will move accordingly, the outward movement thereof being limited when the screw engages the outer end of the slot 21, after 105 which the screw is manipulated to clamp the block with the finger, thereby holding the blade firmly. In this manner the blade is so positioned, as shown in Figure 5 that a person can conveniently grasp the handle 3 and use the blade for cutting open paper containers or cartons. Of course when the de- 110

vice is used for severing twine the blade will be confined between the fingers 6 and 7, therefore the device can be either used associated with the base 1 when severing 5 twine on light packages or removed from the base to sever twine on heavy packages which can not be conveniently lifted.

What is claimed is:

- 10 1. A device of the class described comprising a handle, a collar carried by the handle, a pair of fingers carried by the collar, spaced plates fixed interiorly of one of the fingers, a cutting blade slidable between the plates, and means for sliding and locking the blade in adjusted positions with respect to the fingers.
- 15 2. A device of the class described comprising a base, a handle removably mounted on the base, said handle having an annular shoulder formed therein, a pair of fingers associated with the handle, spaced plates carried by one of the fingers, a blade slidably mounted between the fingers and having its cutting edge slidable between 20 said plates, and means for sliding the blade to an extended position with respect to the fingers and locking the same in such position.
- 25 3. A device of the class described comprising a handle, a blade slidably associated with the handle, means and other means associated therewith to force said blade and said second named means in opposite directions into clamped engagement with the 30 handle.

4. A device of the class described comprising a handle, a blade slidably associated with the handle, a block associated with the blade, and means carried by the block for moving the same and the blade in opposite 40 directions into binding engagement with the handle.

5. A device of the class described comprising a handle, a pair of spaced plates fixed interiorly of the handle and constituting a finger, a cutting blade slidable between the plates, and means for sliding and locking the blade in adjustable positions with respect to the handle. 45

6. A device of the class described comprising a handle, a pair of spaced plates fixed interiorly of the handle and constituting a finger, a cutting blade associated with the plates and means for locking the blade with respect to the handle. 50

7. A device of the class described comprising a handle, a pair of spaced plates fixed interiorly of the handle and constituting a finger, a cutting blade fixed between the plates, and means for locking the blade 55 with respect to the handle.

8. A device of the class described comprising a handle, a finger on the handle, a pair of spaced plates associated with said handle and finger, a cutting blade fixed between the plates, and means for locking the blade with respect to the handle. 60 65

In testimony whereof I affix my signature.

ERWIN R. JONES.
